UNITED STATES PATENT OFFICE

146,432

DESIGN FOR A SHOE

Eduard O. Pielens, Chicago, Ill.

Application October 19, 1946, Serial No. 134,086

Term of patent 14 years

(Cl. D7—7)

To all whom it may concern:

Be it known that I, Eduard O. Pielens, a citizen of no country, residing in Chicago, in the county of Cook and State of Illinois, have invented a new, original, and ornamental Design for a Shoe, of which the following is a specification, reference being had to the accompanying drawing, forming part thereof.

My present application is a continuation-in-part of my copending application Serial No. D. 127,849, filed March 23, 1946.

In the present application Fig. 1 is a front perspective view of a shoe, showing the essential features of my invention in full lines; and

Fig. 2 is a perspective view, on a slightly smaller scale, of the shoe illustrated in Fig. 1 but is taken from the side and rear and slightly from below the sole thereof, clearly to show the arrangement of the flap.

The principal feature of my design resides in the flap covering the juncture between the quarters, which flap is stitched at its forward end to the vamp, but is not stitched along its edges to the quarters.

I claim:

The ornamental design for a shoe, substantially as shown and described.

EDUARD O. PIELENS.
